UNITED STATES PATENT OFFICE.

JOHN J. SAVILLE AND JAMES H. WINSPEAR, OF OMAHA, NEBRASKA.

ELECTRIC CONDUCTOR.

SPECIFICATION forming part of Letters Patent No. 417,095, dated December 10, 1889.

Application filed March 11, 1889. Serial No. 302,900. (No model.)

To all whom it may concern:

Be it known that we, JOHN J. SAVILLE and JAMES H. WINSPEAR, citizens of the United States, residing at Omaha, in the county of Douglas and State of Nebraska, have jointly invented a new and useful improvement in conductors for conveying electric currents from a dynamo to street or railway cars for motor purposes, of which the following is a specification.

Our invention relates to a system of appliances by which electric force is taken from an underground insulated conductor, entirely covered and embedded in insulating material, from points at various distances apart, and conveyed to an electric motor upon a street or railway car. Said appliances and conductors may be placed and operated wholly or in part above or below ground. We attain these objects by the mechanism illustrated in the accompanying drawings, in which—

Figure 1 is a longitudinal section of our device attached to the trucks of a motor-car and in position for operation. Fig. 2 is a plan view of the carrier-frame and carrier-bar in place upon car-trucks. Fig. 3 is a transverse sectional view of our device on line 1 2, in position and in proper relation. Figs. 4 and 5 show power-wire F and lateral wire *g* with insulating material removed, and a section of power-wire and lateral wire; Fig. 6, enlarged view of hinge or joint of carrier-bar; Fig. 7, enlarged view of clamp. Fig. 8 is a sectional elevation of the transmitter. Fig. 9 is a plan of the transmitter. Fig. 10 is a section of the transmitter on the line 3 4. Fig. 11 is a section of the transmitter on line 5 6. Fig. 12 is a perspective view of rubber seat and casing *Z*. Fig. 13 is a perspective view of journal-box *v*.

In Fig. 1, *A* is an iron frame, which rests upon and is attached to the axles of the car-truck inward from the wheels by boxes *a a*. *b b* are arms extending down from frame *A* and united by a cross-bar, (not represented in this view, but represented and marked *c* in Fig. 3,) which serves to support the carrier-bar *B*, and is thus placed in order to avoid the motor machinery, which is placed about the truck-axles. It is obvious that the construction of this frame may be varied to meet the requirements of differently-con-

structed motors. The carrier-bar *B* is iron and in three sections, united by hinges or joints *e e*, which are so constructed as to permit the end section to move vertically and laterally to accommodate the carrier to the curves and grades of the track. (See Fig. 6.) The middle section is attached to the cross-bars *c c*, Fig. 3, by a box *d d*, which permits a slight sliding lateral motion to accommodate the carrier to the side motion of the trucks from any unequal distance of the rails from the center line of the track. The arms *f f* are attached to the middle section of the carrier-bar *B* and terminate in a clamp *g*, (see Fig. 7,) to hold and carry the conducting-wire *C*. The arms *f' f'* are similar to *f f* in all respects, except that they are attached to the end sections of the carrier-bar *B* by a bolt, which permits a slight backward and forward motion of the arm to prevent strain upon the conducting-wire when passing around curves. The guide-wheels *h h* are attached to the arms *f' f'* to keep the conducting-wire in constant proper relation to the transmitter *E*. The guards *i i* are attached to the ends of the carrier-bar *B* by a round bolt, which permits a lateral motion to accommodate it to curves, but does not permit a backward or forward motion. It is slightly curved and grooved to receive the conducting-wire, and serves to protect the wire from injury. It also serves as a fixed point for the spring *k k*, which draws the arms *f' f'* forward, holding the conducting-wire taut. The insulating material is removed from the conducting-wire *C*. *l l l l* are plates, of zinc or other metal, soldered to the conducting-wire *C* and covered with vulcanite or other insulating material, and are constructed with a bead at the upper edge to fit the clamp *g*, Fig. 7. The rod *m m*, with a sliding head *n*, passes through a hole in the carrier-bar *B*, serves to hold in place the spring *o*, which presses down the carrier-bar, and keeps the guide-wheels *h* in place on its track. *p* is a slot or opening into the conduit *D*, through which the arms *f f' f' f'* and guards *i i* pass to carry the conducting-wire *C* along the conduit. The guide-wheel *h* runs upon the bars which form this slot, thus guiding the conducting-wire *C* and holding it at the proper height to form a contact with the transmitter.

E. In the box G the power-wire F is placed for protection from moisture and other injurious influences. It is broken to show the power-wire F where it is attached to the transmitter E. The power-wire F is placed in any convenient position relative to the transmitter to permit the lateral wire q, which is attached to and is a part of the power-wire F, to enter an opening in the side of the case-box K (see Figs. 8, 9, and 10) to connect with the transmitter, as shown in detail in Fig. 8. The power-wire F and the lateral wire q are entirely covered and protected by proper insulating material except at point of contact in the transmitter, as shown in Fig. 8.

In plan view, Fig. 2, the carrier-frame is shown resting upon and attached to the truck-axles by boxes a a a a. c is the cross-bar connecting the arms b, extending down from frame A, and supports the carrier-bar B, which is attached to c by the sliding box d, permitting a slight lateral motion, as described above. The axle is broken to show the cross-bar c beneath. e e are the hinges or joints of the carrier-bar B.

n is the sliding head of the rod m, Fig. 3; f' f', arms of carrier-bar, and h guide-wheel.

In Fig. 3, n is the sliding head to rod m. It consists of an iron frame having three anti-friction wheels r r r, is placed upon the end bars of the carrier-frame A, and has a lateral motion, carrying the rod m and spring o, to keep them in position relative to the carrier-bar B as it moves from side to side in curves of the track. The purpose of this attachment as a whole is to press the carrier-bar B down, so as to keep the guide-wheel h in position on its track. E is the transmitter, suitably located or positioned to have contact with the conducting-wire C. F is the insulated wire having a lateral wire-connection q with the transmitter E.

In Fig. 8, H is a compound wheel composed of a copper wheel s and axle on one side s', which is insulated by rubber or other insulating material t t from the iron casings u u, which are firmly riveted together, the rivets also being insulated from the copper. This wheel is mounted in an iron frame I by means of sliding journal-boxes v v, resting on the spiral spring w w. The frame I is held in a casing-box K by grooved recesses x in the side of the box. On a bench y on the side of the frame I is a rubber seat and casing z, upon which rests the end of the lateral wire q. The end of the wire q is grooved to fit the copper axle s', and the rubber seat and casing z surrounds the wire q and the axle s', thus entirely insulating them and protecting them from all external objects. L is a glass cap over the compound wheel H, to protect it and to form an insulating-guide to insure contact of the conducting-wire C with the copper wheel s of the transmitter. The glass top is bolted to the top of the casing-box K.

The action of the transmitter is as follows: The conducting-wire C, passing over and pressing on the wheel H, forces the axle s' down upon the lateral wire q, thus forming a continuous electrical connection from the power-wire F through the lateral wire q, the copper axle s', the copper wheel s, and the conducting-wire C, to the motor on the car. As soon as the pressure of the conducting-wire C is removed, the spring w w acting upon the sliding journal-boxes v v, raises the axle s' from the lateral wire q, thus entirely breaking electrical connection between the power-wire and external objects.

The usefulness of our invention consists of the use of a conductor entirely covered by and embedded in insulating water-proof material, whereby it may be placed under ground and thereby protected from accidental contact with persons and animals, whose lives might be thus endangered; also, whereby the loss of electric force may be prevented from leakage, or from water, ice, vapor, or other conductors coming in contact with it; also, by action of the transmitter a constant electric current is carried to the motor, the wheel of the transmitter preventing friction and sparking as the conducting-wire comes in contact with it.

What we claim, and desire to secure by Letters Patent, is—

1. The combination of the transmitter E, the power-wire F, lateral wire q, covered and embedded in insulating water-proof material, the frame carried by the car-truck and having pendent arms connected by cross-bars, the carrier-bar formed of sections, having lateral and vertical movement arms depending from said carrier-bar and having clamps, and the conductor-wire, substantially as set forth.

2. The combination of the transmitter E, having the compound wheel H and rubber seat and casting z, and the wires F, q, and C, substantially as set forth.

3. The combination of the transmitter E, the power-wire F, lateral wire q, the frame carried by the car-truck and having pendent arms connected by cross-bars, the carrier-bar formed of sections having lateral and vertical movement arms depending from said carrier-bar and having clamps, wheels carried by the end ones of the lateral arms, springs connecting said end arms to pendent guards of the carrier, and the conductor-wire engaged by said clamps and having connection with the transmitter, substantially as specified.

JOHN J. SAVILLE.
JAMES H. WINSPEAR.
